chine Company, Chicago, Ill., a corporation of
Illinois

Application December 2, 1949, Serial No. 130,654

19 Claims. (Cl. 112—256)

1

This invention relates to sewing machines and more particularly to cyclic lubrication systems provided in such machines intended for high speed operations on the order of 4,000 to 5,000 stitches per minute, or more.

Sewing machines have heretofore been provided with enclosed housings adapted to retain, in a substantially lubricant tight chamber or chambers, the principal operating devices of the machine. However, certain of the moving parts, such as certain of the stitch-forming instrumentalities and the work feeding devices, must be provided outside of the enclosed housing where they may cooperate properly with the work to be stitched. Adequate lubrication of these moving parts, outside of the enclosed housing, presents a more difficult problem. Various means have been suggested for supplying lubricant to these parts from the main reservoir within the housing. However, it is difficult, if not impossible, to supply just enough lubricant to meet the needs of the relatively sliding surfaces and, therefore, a certain excess must be provided which then drips from the surfaces being lubricated. To avoid waste of the lubricant, the excess has heretofore been collected, in some machines, in a bottle or other container attached to the base of the machine at a suitable point and when the bottle has become filled it has been detached and replaced by another bottle and the collected lubricant has been subjected to a filtering or other refining operation to reclaim it. It will be appreciated that such excess lubricant dripping from the stitch-forming and work-feeding devices becomes contaminated with lint and the filler substances used in most fabrics being stitched. Before re-using the collected excess lubricant it is, therefore, necessary to remove from it the lint, filler substances, and other foreign matter which it has accumulated in use. This prior method of dealing with the problem has been reasonably satisfactory, but it has the objection that the main reservoir within the machine becomes depleted of its lubricant, or drops to a dangerously low level, before this condition is observed. As a result, expensive bearings become overheated and are damaged. Also, it has frequently happened that the bottle or other container into which the excess lubricant is directed becomes filled more quickly than expected by the operator and the excess then spills over onto the floor or into the operator's lap.

In an effort to overcome the drawbacks of the above described arrangement, provisions have been made, in some instances, for the collection

5 of the excess lubricant in a sump and the return of this, by gravity, to the reservoir within the main enclosed housing. Filtering means has sometimes been provided between the sump and the main reservoir to remove lint and other solid particles. However, this arrangement has not proved satisfactory due to the fact that the filtering means has very quickly become clogged with the foreign matter and the return of further lubricant to the main reservoir has been prevented or reduced to such a slow rate that an objectionably large amount has accumulated in the sump, even to the point of overflowing from the latter. Moreover, the supply in the main 10 reservoir has been reduced to an objectionably low point.

15 A primary object of the present invention has been to overcome the objections to the schemes heretofore employed and to provide a cyclic system in which lubricant is supplied from a reservoir in a main enclosed housing to parts exterior of said housing and the excess is accumulated and filtered and then returned, as rapidly as accumulated, to the main reservoir. Toward this 20 end, effective pumping means has been included in the system in such a way as to draw the excess lubricant through the filtering means and force it positively into the main reservoir. It has been found that in a system of this character a filtering unit may be used continuously over a relatively long period of time before it becomes clogged to the point that the system fails to function properly. The pumping means, if properly constructed and arranged, has been found to 25 create the effect of a head of lubricant, equivalent to a number of inches, above the filtering medium and this is adequate to carry the lubricant through the filtering means at a sufficiently rapid rate to accomplish the purposes of the invention. 30 It is important, however, that the construction and arrangement of the pump be such that a substantial air-suction is created through the filtering means when no lubricant is present in the sump.

35 A specific object of the invention has been to provide a simple but efficient form of pumping means, in a system of the above indicated character, which will require little power for its operation and yet provide ample suction to draw the oil through the filtering means. In some instances, this has necessitated provisions for driving the pumping means at a more rapid angular speed than that of the main shaft of the machine. As a special feature of this phase of the invention, it has been found particularly effective to

provide a fluid drive for operating the pumping means, this drive being associated with the means within the enclosed housing for distributing the lubricant to the parts requiring lubrication.

Another specific object of the invention has been to provide an easily and quickly removable filtering means for a system of the character described.

A further specific object has been to provide a pumping and filtering assembly which is of simple and inexpensive construction and may be applied to a sewing machine of the character indicated without the necessity of fine tolerances in the relationship between certain of the parts.

Still another specific object of the invention has been to provide a readily replaceable filtering unit, for the purposes specified, which is so simple and inexpensive that it may be discarded after it has become clogged with lint and other solid particles, and readily replaced by a fresh unit of the same character.

Other objects, features, and advantages of the invention will appear from the following detailed description of several embodiments thereof which will now be given in conjunction with the accompanying drawings, in which:

Fig. 1 is a vertical sectional view taken longitudinally through an overedge type of sewing machine embodying the invention;

Fig. 2 is a horizontal sectional view through the machine, taken along the line 2—2 of Fig. 1;

Fig. 3 is a transverse vertical sectional view through the machine, taken along the line 3—3 of Fig. 1;

Fig. 4 is a detail view showing a portion of the oil collecting sump and the filtering means mounted therein;

Fig. 5 is a view, partly in front elevation and partly in vertical section, through a flat bed machine embodying a modified form of the invention;

Fig. 6 is an enlarged detail view, in vertical section, showing the filtering and pumping means employed in the machine of Fig. 5 as assembled on a portion of the latter;

Fig. 7 is an exploded perspective view of the several parts forming the filtering unit of Fig. 6;

Fig. 8 is an exploded perspective view of the pumping means shown in Fig. 6;

Fig. 9 is a top plan view of an element of the pump assembly shown in Fig. 8;

Fig. 10 is a detail view in vertical section through the central portion of the element of Fig. 9;

Fig. 11 is a detail view, in vertical section, showing a modified arrangement for driving the pumping means;

Fig. 12 is an exploded perspective view of the parts of a modified form of filtering unit;

Fig. 13 is an assembled perspective view of the modified filtering unit of Fig. 12; and

Fig. 14 is a vertical sectional view through the filtering unit of Fig. 13 as it is assembled in the bottom of the sewing machine frame.

Turning now to Figs. 1 to 3 inclusive of the drawings, the invention is shown applied to an overedge sewing machine of the type disclosed in the Peterson et al. application, Serial No. 122,204, filed October 19, 1949. For full details as to the construction and operation of this machine reference may be had to said pending application. The machine will be described only generally here. It comprises a main frame having a vertical wall structure 10, a bottom plate 11, and a removable cover 12 forming an oiltight

housing serving to enclose the principal operating parts of the machine and adapted to retain a body of lubricant 13 in a reservoir provided at its bottom. A laterally extending portion 14 at the left end of the vertical wall structure 10 (Fig. 1), is disposed beneath the stitch forming and work feeding devices of the machine, to be briefly described hereinafter, and provides a shallow sump 15 beneath these devices. This extension is also arranged to provide a support for various parts exterior of the main enclosed housing of the machine, including certain pivotally mounted parts, such as a work supporting member 15a and a cover 15b for partially enclosing certain of the work feeding devices. The arrangement is such that access is readily provided to the devices exterior of the main enclosed housing, for adjustment, repair, cleaning purposes, and the like.

The machine is provided with a main driving shaft 16 which extends longitudinally through the main enclosed housing of the frame and projects from the latter at its right end (Fig. 1) to which is secured a combined hand wheel and pulley 17 through which the machine may be driven. Shaft 16 also extends through the left wall of the enclosed housing (Fig. 1) in which it is journaled. The projecting end of the shaft, as will be explained, carries means for operating the work feeding devices of the machine.

The stitch-forming devices include a curved needle 18, a reciprocatory under looper 19, and a reciprocatory and oscillatory overedge looper 20. As explained in said pending Peterson et al. application, either of the loopers may be replaced by a spreader to form a two-thread stitch in lieu of a three-thread stitch. Curved needle 18 is carried by an arm 21 secured to a rock shaft 22 (Fig. 2) which extends through the left hand vertical wall of the enclosed housing into the interior of the latter. Here there is secured to it a clamping member 23 which is connected by a pitman 24 with an eccentric or crank portion of the shaft 16 through which a desired rocking movement is imparted to the shaft 22. Under looper 19 is carried by a reciprocating rod 25 extending through the left vertical wall of the enclosed housing into the interior of the latter. It is reciprocated by means of a link 26 which is pivotally connected at one end to a block 27, secured to the rod, and at its opposite end to the lower end of an arm 28 extending downwardly from a sleeve rockably mounted on a shaft 29. A laterally extending ball pin 30, carried by the sleeve, is connected by a pitman 31 with a spherical eccentric or crank portion 32 of the main shaft 16.

Overedge looper or spreader 20 is carried by a rod 33 which also extends into the interior of the enclosed housing through a bearing in the left-hand vertical wall of the latter. This rod is arranged to be given both a reciprocatory and oscillatory movement. For reciprocating the rod, a block 34 is mounted thereon between a pair of collars secured to the rod, the arrangement being such that the rod may be oscillated within the block, but will be reciprocated upon axial movements of the block. Such movements are imparted by means of a link 35, pivotally connected at one end to the block and pivotally connected at its opposite end to the lower end of an arm 36 freely carried by the shaft 29. A link 37, pivotally connected with the arm 36 at an intermediate point, forms one arm of a toggle, 70 the other arm 38 of which is rockably mounted

on a shaft 38a carried by the frame. A pivot pin 39, connecting the two arms of the toggle, has a ball surface cooperating with a strap 40 at the upper end of a pitman, the lower end of which has a strap 41 cooperating with a spherical eccentric or crank portion of the shaft 16. Oscillatory movements are imparted to the rod 33 by a crank arm 42, at the right end thereof (Fig. 1), which carries a ball pin 43 connected by a pitman 44 with a spherical eccentric or crank portion 45 of the main shaft 12.

The machine is preferably provided with edge trimming mechanism, including a movable blade 46a secured to a rock shaft 47 journaled in and extending through the left-hand vertical wall of the enclosed housing. Within the housing, there is secured to the shaft 47 a clamp 48 having an arm 49 (Fig. 2) which extends downwardly and is connected with one end of a pitman 50, the opposite end of which cooperates with an eccentric or crank portion of the main shaft 16. As more fully explained in said pending Peterson et al. application, the movable trimmer blade 46a cooperates with a stationary trimmer or ledger blade, mounted below the work supporting surface of the machine, to trim the edge of the work just in advance of the stitch forming point.

For advancing the work in the formation of stitches, a main feed dog 51 and an auxiliary feed dog 52, having a differential work feeding movement in relation to the main feed dog, are provided. The main feed dog, only the shank portion of which is shown in Fig. 2, is mounted on the forward end of a feed bar 53, while the auxiliary feed dog is secured to the forward end of an auxiliary feed bar 54. Both feed bars are rockably mounted on a fixed shaft 55 at the rear of the machine. Feed and return movements are imparted to the feed bar 53 by means of a pitman 56 cooperating with an eccentric at the left hand end of the main shaft 16. Similarly, feed and return movements are imparted to the feed bar 54 by means of a pitman 57 cooperating with another eccentric which operates the pitman 56. Both feed bars are given rising and falling movements by an eccentric 58 formed on, or carried by, the main shaft 16 and straddled by forked portions of the two feed bars. For further details as to the construction and operation of the stitch forming, work feeding, and edge trimming mechanisms, reference may be had to said pending Peterson et al. application.

Within the main enclosed housing, an oil throwing member 59 is secured to the shaft 16 between the eccentric or crank 45 and the right-hand wall of the enclosed housing. A hub extension 60 of member 59 is secured by screws 61 to the shaft 16. Member 59 is formed mainly as a radially extending disc, but it carries a laterally extending flange 62 and an inwardly extending flange 63 at the outer end of the flange 62. An annular lubricant retaining channel is thus provided which is of sufficient diameter to have its lower portion extend well below the surface of the lubricant 13 within the housing. The bottom plate 11 of the housing is suitably grooved, as indicated at 64 (Fig. 1) to permit member 59 to be of maximum diameter and yet have adequate clearance in relation to the bottom plate. Upon rotation of the shaft 16, the outer periphery of the member 59, and particularly its flange 62, will pick up oil from the reservoir and disperse the latter as a fine mist, by centrifugal action, throughout the interior of the enclosed housing. At the same time, oil will flow over the inner edge 75

of the flange 63 into the interior of the member and upon rotation of the latter will form a relatively thick film of oil around the inner surface of the flange 62 which tends to rotate with the member 59. The purpose of this will be explained hereinafter. Lubricant dispersed by the outer periphery of member 59 will be distributed over the various relatively moving surfaces of the operating mechanism to insure thorough lubrication of the parts within the housing. Also, a portion of this dispersed lubricant will be picked up by wicks 65, which pass through tubes extending through the left hand vertical wall of the housing. The outer ends of the wicks may be carried to suitable points of the work feeding mechanism to insure proper and adequate lubrication of all of the relatively moving surfaces of the latter. While only two wicks 65 are shown in Fig. 2 it will be understood that as many as may be required for adequate lubrication of the relatively moving parts outside of the enclosed housing should be provided.

Excess lubricant supplied to the work feeding devices will drip therefrom and be collected in the sump 15. An opening 66 is provided at the bottom of this sump substantially centrally between its forward and rear edges. The upper portion of this opening is of larger diameter than the lower portion, thus providing an inwardly extending flange 67 which presents an upwardly facing shoulder to receive and retain a filter pad 68 formed of felt or other suitable material. On the upper face of the pad a disc-like screen member 69 is provided. This may be formed of interwoven mesh material or may be in the form of a perforated plate. The openings of the mesh material, or through the plate, may be of any suitable size. Preferably, however, a screen of about $\frac{1}{4}$ inch mesh, or its equivalent, should be used. This will permit the free flow of the lubricant and the finer particles of impurities but will catch the lint and other relatively large pieces of the impurities. The lint will not clog the openings in the screen. As it accumulates on the top of the screen it may be readily removed by the operator or a service man or it may simply be left and, in effect, add to the filtering action of the felt. A retaining ring 70 is applied over the screen, this having a central aperture of substantially the same diameter as the lower portion of the opening 66. Screws 71 may be employed for securing the retaining ring, screen and filter pad in place. These screws may pass through suitable openings in the several elements and cooperate with threaded openings in the flange 67.

Beneath the opening 66, and communicating therewith, is a horizontally extending bore 72 having a diameter substantially equal to that of the lower portion of opening 66. This bore extends from the outer left end of the frame to the interior of the enclosed housing where it communicates with the reservoir for the lubricant 13. The axis of the bore may suitably be at about the normal lubricant level within the reservoir. The outer left end of the bore is closed by a screw plug 73 which should form a good oil-tight and air-tight seal. A bearing sleeve or bushing 74 is inserted in the inner end of the bore 72 and has journaled therein a shaft 75 provided with a spirally grooved portion 76 cooperating with the bearing surface of the sleeve. As will be explained hereinafter, the form of the groove and the clearance between the grooved portion 76 and the bearing sleeve 74 is preferably of a predetermined character to

insure an effective pumping action. It is important that the pump formed by the spirally grooved portion of the shaft and its bearing sleeve should be capable not only of pumping the maximum amount of lubricant delivered to the sump 15 but it must also be capable of creating air suction so as to assist in drawing lubricant through the filtering means under a suitable head.

At an intermediate point the shaft 75 is journaled in a bushing 78 carried by a vertically extending wall within the housing. Collars 71, secured to the shaft at opposite sides of the bushing 78, serve to take the axial thrusts of the shaft and maintain the latter in the desired axial position. At its extreme right end, the shaft has secured thereto a hub 79 of an impeller 80. The latter is supported by the shaft within the oil distributing member 59 and has only a small clearance at its lowermost point in relation to the flange 62 of member 59. Impeller 80, as best shown in Fig. 3, is formed with a disc-like portion 81 and a series of flanges or projections 82 which extend radially from the hub and in an axial direction from the face of the disc 81. A series of pockets 83 is thus provided parallel with and adjacent to the inner face of the disc-like portion of member 59. These pockets are open at their outer, larger ends.

Upon rotation of the main shaft 16 of the machine, the member 59 will be revolved at the same angular speed and will create a moving band of lubricant around the inner periphery of the flange 62. This band of lubricant will be carried around at substantially the same circumferential speed as the flange 62. As the revolving lubricant strikes the flanges 82 and enters the pockets 83, it will serve to effect a fluid drive connection between members 59 and 80. Due to the difference in the relative diameters of these members, the member 80 will be rotated at a substantially higher angular speed than member 59. In the construction illustrated member 80, and hence shaft 75, will be rotated at about 3 times the angular speed of the main shaft 16. This will cause the spiral groove pump 76 to create a substantial pumping action and air-suction. It has been found more than adequate to draw the lubricant from the sump 15 as rapidly as the excess lubricant accumulates therein. This pumping action is effective for this purpose for a substantial period of time, in spite of the accumulation of foreign matter on and in the filtering means. When this accumulation reaches the point at which it retards too much the flow of lubricant through the filtering means, the latter may readily be removed for cleaning and then replaced, or a new filter and screen unit may be substituted. It is simply necessary to remove the screws 71 to permit such replacement.

Turning now to Figs. 5 to 10 inclusive, there is shown an adaptation of the invention to a flat bed machine of the type disclosed in the Peterson et al. application Ser. No. 58,222, filed November 14, 1948. This machine has a frame providing a base portion 84 with a work supporting surface 85, a vertical standard 86 rising from one end of the base and an overhanging arm 87 extending laterally from the vertical standard over the base and terminating in a needle head 88. A rotary drive shaft 89 is provided in the base, this being journaled in suitable bearings in a wall 90 at the left end of the frame (Fig. 5), in a plurality of intermediate

walls 91 and 92, and in an outer wall 93 at the right-hand end of the frame. On the end of the shaft which projects outwardly from the frame, there is secured a combined handwheel and pulley 94 through which power may be supplied for driving the machine.

5 A needle bar 95 is mounted for vertical reciprocation in the needle head and carries a plurality of needles 96 at its lower end. Reciprocation of the needle bar is effected through connection with one end of a lever 97, the opposite end of which is connected through a pitman 98 with a crank 99 on the shaft 89. Cooperating with the needles below the work support is a 4-motion looper 100 secured to a carrier 101 pivotally mounted on a rock member 102. Suitable connections from the shaft 89 serve to rock the member 102 to impart needle avoid movements to the looper. Connections are also provided from the main shaft for swinging the carrier 101 about its pivot to impart loop seizing and shedding movements to the looper. These latter connections include a pitman 103 having ball pin connections with an intermediate point on the carrier and with the upper end of an arm 104. Suitable work feeding devices are included in the machine, these being, in part, shown at 105. The feed stroke and return movements are imparted to the feed dogs (not shown) by an eccentric at the outer end of the shaft 89 cooperating with a link 106. For further details as to the construction and operation of the stitch-forming and work feeding devices of the machine, reference may be had to said Peterson et al. application Serial No. 58,222.

30 An enclosed oil reservoir is provided within the frame between the walls 91 and 92 and between the latter and the outer wall 93. Of course the front and rear walls and the top and bottom members of the frame complete the enclosure of the reservoir. In effect, there is but a single reservoir which is divided into two parts by the wall 92; the parts are inter-connected by an opening, or series of openings, 107 near the bottom of the frame for the free passage of lubricant through the wall 92. Lubrication of the parts in the vertical standard and overhanging arm is effected by spray generated within this portion of the frame through the action of the crank 99 and other parts which dip periodically into the oil in the reservoir. Lubrication of the relatively moving parts outside of the enclosed chamber, including the looper mechanism and work feeding mechanism, is effected by delivery of oil from the reservoir within the enclosed housing through various channels in the frame and suitable wicking. Thus, oil is delivered from the reservoir through openings 108 (Fig. 6) in a portion of the wall 91, these openings leading to a vertical passage 109 in the wall. Passage 109 is connected by a transverse passage 110 with various other channels in the base, including horizontal, transversely extending passages 111 (Fig. 5) near the left end of the base and vertical passages 112 communicating with the passages 111. Suitable wicking 113, receiving lubricant from within one or another of the various passages, serves to deliver the lubricant to the surfaces of the loop-taking and work-feeding mechanism requiring lubrication. The ball-pin connection between the pitman 103 and arm 104 may be lubricated by wicking 113a extending through a tube which communicates with the interior of the enclosed housing and receives lubricant directly from the mist therein and car-

ries this lubricant to a point in the path of movement of the connection mentioned. It will be understood that other passages and wicking and the like may be provided to supply lubricant to all of the parts in the base outside of the enclosed housing which require lubrication. Reference may be had to said Peterson et al. application, Serial No. 58,222 for additional details as to the lubricant distribution system.

Excess lubricant delivered to the various exterior parts in the base will drip therefrom and be collected in a sump 114 which is suitably positioned and shaped to catch the excess from all points. At a low point in the sump an opening of suitable size is provided, this being largely closed by a plug 115 (Figs. 5 and 6) having a pressed fit in relation to the walls of the opening. The opening is preferably of larger diameter at its lower end than at its top and thus provides a shoulder against which a gasket 116 may be forced by the plug 115. Openings 117 through the enlarged portion of the plug are adapted to receive a series of machine screws (not shown) for securing the plug to the bottom of the sump. It will be understood that gasket 116 has alined openings and the bottom of the sump has alined screw threaded holes to receive the screws. Through the center of the plug an axially extending opening 118 is provided, this being of relatively small diameter at its upper end and increasing in diameter in several steps toward its lower end to provide suitable shoulders. A screw plug 119 cooperates with threads formed in the wall of the opening, at its lower end, to effect a lubricant tight closure. Above the screw plug a spring 120 is mounted, this spring serving to retain filtering means, comprising a pad 121 formed of felt or the like and a screen or perforated plate 122. These are forced by the spring against a shoulder provided by the reduced diameter of the opening 118 at its upper end.

Spring 120 is within a lubricant receiving pocket between the filtering means and the top of the screw plug 119. This pocket communicates, through a radial passage 123 extending through the enlarged portion of the plug 115, with a tube 124. The latter may be formed of any suitable material, such as copper, brass, or an appropriate plastic. At its opposite end, the tube 124 is inserted in a radial passage 125 in an enlarged head portion of a bearing sleeve 126. The latter has a pressed fit engagement with an opening through the bottom of the reservoir of the enclosed housing. Tube 124 is received by a groove or recess 127, formed by milling or the like, in the bottom of the frame. To effect an oiltight seal between the bearing sleeve 126 and the bottom of the reservoir a gasket 128 may be provided, this being squeezed by the enlarged head of the bearing sleeve against a shoulder formed by the reduced portion of the opening through the bottom of the reservoir. Holes 129 extending through the enlarged head of the bearing sleeve are adapted to receive machine screws (not shown) for securing the sleeve to the frame. Gasket 128 is provided with suitable holes to receive the screws and the cooperating shoulder at the bottom of the reservoir is provided with threaded holes to receive the ends of the screws.

To insure a lubricant tight connection between the tube 124 and the plug 115 and bearing sleeve 126, it has been found desirable to assemble these three parts separately and then apply them as a unit to the machine frame. To

avoid unduly fine tolerances in the relative position of the openings which receive the plug 115 and bearing sleeve 126, it has been found desirable to provide the tube 124 with a slight bend 5 and to form this of flexible material, so that the tube may be bent to a greater or lesser extent to permit the plug and bearing sleeve to be inserted freely in their openings. Groove or recess 127 in the bottom of the frame should be of sufficient width to accommodate the bend in the tube.

10 A recess 130 is provided in the lower end of the bearing sleeve 126, centrally thereof, and this recess is screw threaded to receive a threaded plug 131 for closing the bottom of the recess. Plug 15 131 has a reduced shank portion 132 which extends upwardly into the recess, but leaves an annular pocket around the same which communicates with the radial passage 125. Above the recess 130, the bearing sleeve is provided with an axial bore of smaller diameter to receive a spirally grooved shaft 133. The lower end of this shaft is carried by the top of the shank 132 of the screw plug which may be suitably adjusted to hold the shaft at the desired elevation. At its 20 upper end, the shaft 133 carries a bevel gear 134 which is secured to the shaft by a screw 135. Bevel gear 134 meshes with another bevel gear 136 secured to the main drive shaft 89. Accordingly, it will be apparent that upon operation of the machine the spirally grooved shaft 133 will be rotated, the direction of rotation being such as to force any lubricant in the groove upwardly along the bearing surface of sleeve 126. Bevel gears 134 and 136 may be of any desired relative 25 30 35 diameters to cause the shaft 133 to be driven at an angular speed equal to or greater or less than that of shaft 89.

35 Plug 115 is of sufficient size to provide good access to the parts above it, for repair, adjustment and cleaning, when the plug is removed. Bearing sleeve 126 is of sufficient outside diameter to permit the pump unit, including the bevel gear 134, to be inserted through the opening in the bottom of the reservoir. When removed, it also provides access to certain of the devices within the reservoir.

40 The form and dimensions of the various lubricant passages and pockets associated with the pumping means, provided by the shaft 133, have been found to be of considerable importance to the proper functioning of the system. For example, it has been found important to the efficient functioning of the pump that the lubricant be supplied to the spiral groove through a 45 radial passage 137 (Fig. 6) just above the bottom of the bearing surface. To supply lubricant to this passage a series of radial passages 138, four being shown, (Figs. 9 and 10) is provided from the exterior surface of the shank 132 to the center thereof. At the center of the shank the 50 passages 138 communicate with a somewhat larger vertical passage 139. This, in turn, communicates with an axially extending bore 140 (Fig. 8) in the bottom of the shaft 133. Radial passage 137 extends from the bore 140 adjacent, but not quite at, its upper end. Passage 137 imparts a centrifugal pumping action to the lubricant which assists in creating the pumping and suction action of the unit as a whole. For efficient operation, it has also been found desirable to form the spiral groove in the shaft 133 of greater width than depth. Excellent results have been obtained from the use of a groove having a width of $3/64$ of an inch and having a depth of 55 $1/64$ of an inch. It has also been found desirable

to provide the groove with a relatively low pitch. Eight turns to the inch have been found to produce very effective results. If the helix angle is made smaller, by increasing the number of turns to the inch, the amount of metal left between grooves becomes objectionably small. However, if eight turns of the spiral are provided per inch in a shaft having an outside diameter of .468 inch, the helix angle is such as to provide good results and enough metal is left between successive turns of the groove to afford a good bearing action. If the shaft is of smaller diameter the helix angle will increase and the pumping capacity will decrease. Also it has been found important to provide the groove with smooth walls and preferably it is formed with a rectangular cross-section. Friction losses are reduced by providing smooth walls to the groove and the pumping action is made more effective, and the capacity of the pump increased, by having a groove of greater width than depth. A possible explanation for this is that the greater width of the groove increases the frictional resistance to the turning of the lubricant with the shaft, since it then has a greater surface in contact with the bearing sleeve. By thus retarding the rotation of the lubricant it is advanced more rapidly along the helix as the shaft turns relative to the lubricant.

The foregoing are important considerations which contribute materially to the success of the invention. Certain spirally grooved shafts originally employed were found to function in a reasonably satisfactory way for a brief interval, but they then become air locked and the system was rendered inoperative until the machine was stopped and then started again. A total clearance of about .001 of an inch has been found desirable between the outside diameter of the shaft and the inside diameter of the bearing sleeve. However, some variation in this clearance has been found permissible without substantial variation in the effectiveness of the pump. It has also been found desirable to provide an enlarged recess 141 at the top of the bearing sleeve so as to provide a small annular pocket into which the lubricant is forced and from which it spills over the edge of the bearing sleeve back into the reservoir. A part of the lubricant is picked up by the surfaces of the bevel gear 134 and is thrown, in finely dispersed form, from the periphery of the latter to assist in lubricating the parts within the enclosed housing.

In tests conducted upon a unit having the form and dimensions set forth above it has been found that with the machine, and also the pump, operating at 4,000 R. P. M., the pump is capable of delivering 28 ccs. of lubricant per minute. It has also been found that the pump, when so constructed and operated at a speed of 4,000 R. P. M., is capable of creating a suction equivalent to a head of about 4" of oil. This has been found adequate to draw the lubricant through the filtering means substantially as quickly as it accumulates in the sump 114, even after the filter has been used for some time and has become partially plugged with foreign matter. When the filter becomes clogged with foreign particles to such an extent that the system does not operate efficiently, the screw plug 119 may be readily removed and a new pad and screen inserted, or the old pad and screen may be cleaned and reintroduced.

In Fig. 11 a modified form of the invention is shown in which the pump, in the form of a

spirally grooved shaft 133a, is driven frictionally from the main shaft 89a. For this purpose a friction disc 142 is secured to the upper end of shaft 133a and this cooperates with the periphery of a friction disc or wheel 143 secured to the main shaft. The relative diameters of the disc 142 and wheel 143 may be varied to suit the requirements of the system. In the arrangement shown, the spirally grooved shaft 133a will be driven at a somewhat slower angular speed than the main shaft. Should it be found necessary or desirable to drive the grooved shaft at a higher speed the diameters of the driving and driven members may be made equal or the relation between their diameters may be reversed. The pumping action of the system varies substantially directly with the speed of rotation of the grooved shaft.

In Figs. 12, 13 and 14 there is shown a modified form of filtering means which may suitably be made and sold as a unit. It comprises a screw plug 144 which serves the purpose of the screw plug 119, of Fig. 6, but has an upwardly extending portion 145 arranged to receive and extend into the lower open end of a cup-shaped screen member 146. The latter may have a sufficiently tight fit in relation to the portion 145 to be held frictionally thereon, or it may be secured thereto in any other suitable way. Within the screen member 146 there is held a filter pad 147, formed of felt or the like, this being retained within the member 146 by means of a split spring ring 148. The arrangement is such that a small lubricant receiving pocket 149 is provided between the upper end of projection 145 and the bottom of the filter pad 147. A radially extending passage 150, corresponding with passage 123 of Fig. 6, communicates with pocket 149 through the vertical wall of the screen member 146. It will be understood that the unit to be inserted as a separate assembly may include all of the parts illustrated in Figs. 12 and 13. However, the filtering units to be sold may comprise only the three upper elements of Fig. 12, i. e., the screen member 146, the filter pad 147 and the retaining ring 148, these being usable interchangeably on the screw plug 144.

While several embodiments of the invention have been disclosed in considerable detail, it will be understood that various modifications may be made in each embodiment without departing from the principles and scope of the invention. Features disclosed in connection with one embodiment may be incorporated in another. Thus, the dimensions of the corresponding parts of the pumping means described in connection with Figs. 5 to 10 inclusive, may be followed in the production of the embodiment of Figs. 1 to 4. In all forms of the invention, the spirally grooved member of the pump is preferably formed of stainless steel or other similar metal which is not subject to corrosion when the machine is idle for a substantial period of time.

What we claim is:

1. In a sewing machine, a frame having an enclosed portion providing a lubricant retaining reservoir, a rotary drive shaft extending through said enclosed portion, work feeding devices outside of said reservoir, connections from said shaft for operating said devices, means for delivering lubricant from said reservoir to said devices in substantial excess of the lubricant consumption thereof, a sump beneath said devices for collect-

13

ing excess lubricant therefrom, means providing a conduit for returning lubricant from said sump to said reservoir, filtering means mounted in a readily accessible portion of said frame for removing solid particles from said lubricant before it is returned to said reservoir, said filtering means being relatively small and of inadequate capacity to handle by gravity said excess delivered to said devices, and pumping means operated by rotation of said drive shaft for drawing lubricant through said filtering means and forcing it into said reservoir, said pumping means being constructed and arranged to provide a suction head on the oil above the filter.

2. In a sewing machine, a frame having an enclosed portion providing a lubricant retaining reservoir, a rotary drive shaft extending through said enclosed portion, work feeding devices outside of said reservoir, connections from said shaft for operating said devices, means for delivering lubricant from said reservoir to said devices in substantial excess of the lubricant consumption thereof, a sump beneath said devices for collecting excess lubricant therefrom, means providing a conduit for returning lubricant from said sump to said reservoir, filtering means mounted in a readily accessible portion of said frame for removing solid particles from said lubricant before it is returned to said reservoir, said filtering means being relatively small and of inadequate capacity to handle said excess delivered to said devices, and pumping means comprising a bearing sleeve and a spirally grooved member within said sleeve operated by rotation of said drive shaft and arranged to create a suction for drawing lubricant through said filtering means and forcing it into said reservoir.

3. In a sewing machine, a frame having an enclosed portion providing a lubricant retaining reservoir, a rotary drive shaft extending through said enclosed portion, work feeding devices outside of said reservoir, connections from said shaft for operating said devices, means for delivering lubricant from said reservoir to said devices in substantial excess of the lubricant consumption thereof, a sump beneath said devices for collecting excess lubricant therefrom, means providing a conduit for returning lubricant from said sump to said reservoir, filtering means mounted in a readily accessible portion of said frame for removing solid particles from said lubricant before it is returned to said reservoir, said filtering means being relatively small and of inadequate capacity to handle said excess delivered to said devices, and rotary pumping means operated by rotation of said drive shaft and arranged to create a suction for drawing lubricant through said filtering means and forcing it into said reservoir, said pumping means being operated at higher angular velocity than said shaft.

4. In a sewing machine, a frame having an enclosed portion providing a lubricant retaining reservoir, a rotary drive shaft extending through said enclosed portion, work feeding devices outside of said reservoir, connections from said shaft for operating said devices, means for delivering lubricant from said reservoir to said devices in substantial excess of the lubricant consumption thereof, a sump beneath said devices for collecting excess lubricant therefrom, means providing a conduit for returning lubricant from said sump to said reservoir, filtering means for removing solid particles from said lubricant before it is returned to said reservoir, said filtering means being relatively small and of inadequate capacity

14

to handle by gravity said excess delivered to said devices pumping means comprising a bearing sleeve and a spirally grooved rotary member within said sleeve and arranged to create a suction for drawing lubricant through said filtering means and forcing it into said reservoir, and connections from said drive shaft for operating said spirally grooved member at higher angular velocity than said shaft, said connections comprising hydraulic means operated by said shaft for imparting motion to said spirally grooved member through said lubricant.

5. In a sewing machine, a frame having an enclosed portion providing a lubricant retaining reservoir, a rotary drive shaft extending through said enclosed portion, work feeding devices outside of said reservoir, connections from said shaft for operating said devices, means for delivering lubricant from said reservoir to said devices in substantial excess of the lubricant consumption thereof, a sump beneath said devices for collecting excess lubricant therefrom, means providing a conduit for returning lubricant from said sump to said reservoir, filtering means for removing solid particles from said lubricant before it is returned to said reservoir, said filtering means being relatively small and of inadequate capacity to handle by gravity said excess delivered to said devices pumping means comprising a bearing sleeve and a spirally grooved rotary member within said sleeve and arranged to create a suction for drawing lubricant through said filtering means and forcing it into said reservoir, and connections from said drive shaft for operating said spirally grooved member at higher angular velocity than said shaft, said connections comprising an impeller connected with said member for rotating the same and means carried by said shaft for causing said lubricant to drive said impeller.

6. In a sewing machine, a frame having an enclosed portion providing a lubricant retaining reservoir, a rotary drive shaft extending through said enclosed portion, work feeding devices outside of said reservoir, connections from said shaft for operating said devices, means for delivering lubricant from said reservoir to said devices in substantial excess of the lubricant consumption thereof, a sump beneath said devices for collecting excess lubricant therefrom, means providing a conduit for returning lubricant from said sump to said reservoir, filtering means for removing solid particles from said lubricant before it is returned to said reservoir, said filtering means being relatively small and of inadequate capacity to handle by gravity said excess delivered to said devices pumping means comprising a bearing sleeve and a spirally grooved rotary member within said sleeve and arranged to create a suction for drawing lubricant through said filtering means and forcing it into said reservoir, and connections from said drive shaft for operating said spirally grooved member at higher angular velocity than said shaft, said connections comprising an impeller connected with said member for rotating the same and means carried by said shaft adapted to engage said lubricant to disperse the same within said enclosed portion of the frame for delivery to said first mentioned means and to direct the same against said impeller to drive the latter.

7. An overedge sewing machine having a frame with an enclosed portion providing a lubricant retaining reservoir, said frame having

a work supporting surface, a rotary drive shaft below said surface and extending through said enclosed portion, a rock shaft connected with said drive shaft within said enclosed portion for oscillation by the latter, said rock shaft extending to a point exterior of said enclosed portion above said surface, needle carrying means connected with said rock shaft for reciprocation of the needle through said surface, complementary stitch forming means cooperating with said needle to form overedge stitches, work feeding means beneath said surface exterior of said enclosed portion of the frame, connections from said drive shaft for operating said complementary stitch forming means and said work feeding means, at least a portion of said connections being exterior of said enclosed portion of the frame, means operated by said drive shaft for delivering lubricant from said reservoir to said exterior connections in substantial excess of the lubricant consumption thereof, a sump beneath said surface for collecting excess lubricant supplied to said exterior connections, filtering means mounted in a readily accessible position at the bottom of said sump, said filtering means being relatively small and of inadequate capacity to handle by gravity said excess delivered to said devices, and pumping means connected with said drive shaft and driven thereby for creating a suction beneath said filtering means and drawing lubricant through said filtering means and returning it to said reservoir.

8. An overedge sewing machine having a frame with an enclosed portion providing a lubricant retaining reservoir, said frame having a work supporting surface, a rotary drive shaft below said surface and extending through said enclosed portion, a rock shaft connected with said drive shaft within said enclosed portion for oscillation by the latter, said rock shaft extending to a point exterior of said enclosed portion above said surface, needle carrying means connected with said rock shaft for reciprocation of the needle through said surface, complementary stitch forming means cooperating with said needle to form overedge stitches, work feeding means beneath said surface exterior of said enclosed portion of the frame, connections from said drive shaft for operating said complementary stitch forming means and said work feeding means, at least a portion of said connections being exterior of said enclosed portion of the frame, means operated by said drive shaft for delivering lubricant from said reservoir to said exterior connections in substantial excess of the lubricant consumption thereof, a sump beneath said surface for collecting excess lubricant supplied to said exterior connections, filtering means mounted in a readily accessible position at the bottom of said sump, said filtering means being relatively small and of inadequate capacity to handle by gravity said excess delivered to said devices, a passage communicating with the discharge side of said filtering means and with said reservoir, and a spirally grooved member in said passage driven by said drive shaft for creating a suction beneath said filtering means drawing lubricant through said filtering means and returning it to said reservoir.

9. In a sewing machine, a frame having an enclosed portion providing a lubricant retaining reservoir, a rotary drive shaft extending through said enclosed portion, work feeding devices outside of said reservoir, connections from said shaft for operating said devices, means for delivering

lubricant from said reservoir to said devices in substantial excess of the lubricant consumption thereof, a sump beneath said devices for collecting excess lubricant therefrom, filtering means mounted in a readily accessible portion of said frame at the bottom of said sump, said filtering means being relatively small and of inadequate capacity to handle by gravity said excess delivered to said devices, an enclosed pocket beneath said sump, a cylindrical passage connecting said pocket with said reservoir, a rotary spirally grooved member in said passage and substantially filling the same, and means for rotating said member from said drive shaft, said member and passage being constructed and arranged to provide a suction head on the oil above the filter upon rotation of said member.

10. In a sewing machine, a frame having a work supporting surface and an enclosed portion below the level of said surface providing a lubricant reservoir, a rotary drive shaft within said enclosed portion and extending therefrom to a point beneath said work supporting surface, work feeding means beneath said surface exterior of said enclosed portion, connections from said shaft exterior of said enclosed portion for actuating said work feeding means, means for delivering lubricant from said reservoir to said connections upon operation of said shaft in substantial excess of the lubricant consumption of said connections, a sump beneath said connections for collecting excess lubricant therefrom, a pump driven by said shaft for returning lubricant from said sump to said reservoir, said pump comprising a spirally grooved shaft within said reservoir and a bearing sleeve surrounding said shaft, and oil filtering means mounted in a readily accessible portion of said frame between said sump and said pump, said filtering means being relatively small and of inadequate capacity to handle by gravity said excess delivered to said devices, said pump being constructed and arranged to provide a suction head on the oil above the filter.

11. In a sewing machine, a main drive shaft, a frame having an enclosed housing providing a lubricant reservoir and a work supporting surface extending beyond said housing, work feeding means beneath said surface exterior of said housing and driven by said shaft, means for supplying lubricant from said reservoir to said work feeding means upon operation of said shaft in substantial excess over the requirements of said work feeding means, a sump beneath said work feeding means for collecting excess lubricant therefrom, filtering means associated with said sump and carried by said frame in a readily accessible position for removing solid particles from the lubricant delivered from said sump, and a pump driven by said shaft connected with the discharge side of said filtering means and arranged to create a suction for drawing lubricant therethrough and returning the same to said reservoir, said pump comprising a spirally grooved shaft portion and a bearing sleeve surrounding said portion, the groove in said shaft portion being of greater width than its depth.

12. In a sewing machine, a main drive shaft, a frame having an enclosed housing providing a lubricant reservoir and a work supporting surface extending beyond said housing, work feeding means beneath said surface exterior of said housing and driven by said shaft, means for supplying lubricant from said reservoir to said work feeding means upon operation of said shaft

in substantial excess over the requirements of said work feeding means, a sump beneath said work feeding means for collecting excess lubricant therefrom, filtering means associated with said sump and carried by said frame in a readily accessible position for removing solid particles from the lubricant delivered from said sump, and a pump driven by said shaft connected with the discharge side of said filtering means and arranged to create a suction for drawing lubricant therethrough and returning the same to said reservoir, said pump comprising a spirally grooved shaft portion and a bearing sleeve surrounding said portion, the groove in said shaft portion being about $\frac{3}{64}$ of an inch wide and about $\frac{1}{64}$ of an inch deep.

13. In a sewing machine, a main drive shaft, a frame having an enclosed housing providing a lubricant reservoir and a work supporting surface extending beyond said housing, work feeding means beneath said surface exterior of said housing and driven by said shaft, means for supplying lubricant from said reservoir to said work feeding means upon operation of said shaft in substantial excess over the requirements of said work feeding means, a sump beneath said work feeding means for collecting excess lubricant therefrom, filtering means associated with said sump and carried by said frame in a readily accessible position for removing solid particles from the lubricant delivered from said sump, and a pump driven by said shaft connected with the discharge side of said filtering means and arranged to create a suction for drawing lubricant therethrough and returning the same to said reservoir, said pump comprising a spirally grooved shaft portion and a bearing sleeve surrounding said portion, the groove in said shaft portion being of greater width than its depth, and having a helix angle about equal to that of a spiral having 8 turns to the inch around a shaft .468 inch in diameter.

14. In a sewing machine, a main drive shaft, a frame having an enclosed housing providing a lubricant reservoir and a work supporting surface extending beyond said housing, work feeding means beneath said surface exterior of said housing and driven by said shaft, means for supplying lubricant from said reservoir to said work feeding means upon operation of said shaft in substantial excess over the requirements of said work feeding means, a sump beneath said work feeding means for collecting excess lubricant therefrom, filtering means associated with said sump and carried by said frame in a readily accessible position for removing solid particles from the lubricant delivered from said sump, and a pump driven by said shaft connected with the discharge side of said filtering means and arranged to create a suction for drawing lubricant therethrough and returning the same to said reservoir, said pump comprising a spirally grooved shaft portion and a bearing sleeve surrounding said portion, said shaft portion having an axial bore, the lubricant being delivered axially into said bore and discharged radially therefrom to the spiral groove in said shaft portion.

15. In a sewing machine, a main drive shaft, a frame having an enclosed housing providing a lubricant reservoir and a work supporting surface extending beyond said housing, work feeding means beneath said surface exterior of said housing and driven by said shaft, means for supplying lubricant from said reservoir to said work feeding means upon operation of said shaft

in substantial excess over the requirements of said work feeding means, a sump beneath said work feeding means for collecting excess lubricant therefrom, filtering means associated with said sump and carried by said frame in a readily accessible position for removing solid particles from the lubricant delivered from said sump, a pump driven by said shaft connected with the discharge side of said filtering means and arranged to create a suction for drawing lubricant therethrough and returning the same to said reservoir, said pump comprising a spirally grooved shaft connected with said drive shaft and a bearing sleeve surrounding the grooved portion of said grooved shaft, and a stationary member abutting one end of said grooved shaft, said member and said grooved shaft having aligned axial passages and spaced radial passages for the delivery of lubricant from said filtering means to the spiral groove.

16. In a sewing machine, a main drive shaft, a frame having an enclosed housing providing a lubricant reservoir and a work supporting surface extending beyond said housing, work feeding means beneath said surface exterior of said housing and driven by said shaft, means for supplying lubricant from said reservoir to said work feeding means upon operation of said shaft in substantial excess over the requirements of said work feeding means, a sump beneath said work feeding means for collecting excess lubricant therefrom, filtering means associated with said sump and carried by said frame in a readily accessible position for removing solid particles from the lubricant delivered from said sump, a pump driven by said shaft connected with the discharge side of said filtering means and arranged to create a suction for drawing lubricant therethrough and returning the same to said reservoir, said pump comprising a spirally grooved shaft connected with said drive shaft and a bearing sleeve surrounding the grooved portion of said grooved shaft, and a plug carried by said sleeve, said plug having a reduced portion abutting the end of said grooved shaft and providing a lubricant receiving pocket in said sleeve communicating with the discharge side of said filtering means, said plug having intercommunicating radial and axial passages, the radial passage communicating with said pocket and the axial passage communicating with a longitudinally extending passage in said grooved shaft, said grooved shaft having also a transversely extending passage connecting said longitudinal passage with the grooved surface of said grooved shaft.

17. In a sewing machine, a main drive shaft, a frame having an enclosed housing providing a lubricant reservoir and a work supporting surface extending beyond said housing, work feeding means beneath said surface exterior of said housing and driven by said shaft, means for supplying lubricant from said reservoir to said work feeding means upon operation of said shaft in substantial excess over the requirements of said work feeding means, a sump beneath said work feeding means for collecting excess lubricant therefrom, lubricant filtering and pumping means arranged to be applied as a unit to a readily accessible portion of said frame for connecting said sump with said reservoir, and connections from said drive shaft to said unit for operating the pumping means, said pumping means being constructed and arranged to provide a suction head on the oil through the filter.

18. In a sewing machine, a main drive shaft,

a frame having an enclosed housing providing a lubricant reservoir and a work supporting surface extending beyond said housing, work feeding means beneath said surface exterior of said housing and driven by said shaft, means for supplying lubricant from said reservoir to said work feeding means upon operation of said shaft in substantial excess over the requirements of said work feeding means, a sump beneath said work feeding means for collecting excess lubricant therefrom, said sump and said reservoir being provided with openings through the bottom walls thereof, closure members inserted in said openings, each of said members having a lubricant receiving pocket, interconnecting means providing a passage for lubricant between said pockets, readily removable filtering means associated with the member in the bottom of said sump, pumping means in the member in the bottom of said reservoir arranged to create a suction for drawing lubricant through said filtering means and forcing it into said reservoir, and connections from said drive shaft for operating said pumping means.

19. In a sewing machine, a main drive shaft, a frame having an enclosed housing providing a lubricant reservoir and a work supporting surface extending beyond said housing, work feeding means beneath said surface exterior of said housing and driven by said shaft, means for supplying lubricant from said reservoir to said work feeding means upon operation of said shaft in substantial excess over the requirements of said work feeding means, a sump beneath said work

5

feeding means for collecting excess lubricant therefrom, said sump and said reservoir being provided with openings through the bottom walls thereof, closure members inserted in said openings, each of said members having a lubricant receiving pocket, interconnecting means providing a passage for lubricant between said pockets, readily removable filtering means associated with the member in the bottom of said sump, pumping means in the member in the bottom of said reservoir arranged to create a suction for drawing lubricant through said filtering means and forcing it into said reservoir, and connections from said drive shaft for operating said pumping means, said members and said interconnecting means being formed as a unit adapted to be applied in assembled relation to said frame.

10

15

means in the member in the bottom of said reservoir arranged to create a suction for drawing lubricant through said filtering means and forcing it into said reservoir, and connections from said drive shaft for operating said pumping means, said members and said interconnecting means being formed as a unit adapted to be applied in assembled relation to said frame.

GEORGE SAUER.
